UNITED STATES PATENT OFFICE.

SIEGFRIED ADLER, OF CHICAGO, ILLINOIS, ASSIGNOR TO COMMON SENSE NOVELTY COMPANY, OF CHICAGO, ILLINOIS, A CORPORATION.

DISPLAY DEVICE.

1,135,484.

Specification of Letters Patent.

Patented Apr. 13, 1915.

Application filed October 10, 1913. Serial No. 794,380.

To all whom it may concern:

Be it known that I, SIEGFRIED ADLER, a citizen of the United States, residing at Chicago, in the county of Cook and State of Illinois, have invented a certain new and useful Improvement in Display Devices, of which the following is a specification.

My invention relates to display devices such as collapsible signs or placards sometimes called "shadow box signs", and the object of the invention is to so construct a device of this character as to make it practicable to ship the sign in "knocked down" condition.

As a result of my invention, the entire device may be laid out flat, and may be readily set up upon reaching the merchant who is to display it.

In the best form all of the parts are permanently connected together so that they cannot become separated from each other during shipment, nor parts of the device lost. Furthermore, by having the parts all permanently fastened together the device is more durable and the "set up" state more apt to remain undisturbed.

I accomplish my objects by the construction shown in the accompanying drawings, in which

Figure 1 is a front face view of the device as it appears when in use. Fig. 2 is a rear view of the parts in the state shown in Fig. 1. Fragments of the frame are broken away at the internal margin for better indicating the interfitting construction. Fig. 3 is a rear view showing the parts knocked down ready for shipment. Fig. 4 is a central vertical sectional view of the device in condition of use. Fig. 5 is a similar sectional view but shows the device in knocked down condition.

Similar numerals refer to similar parts throughout the several views.

The frame, which has a rectangular central opening 1^a consists of cardboard, wood, wood fiber or any other suitable material. The internal edges of the frame surrounding the central opening thereof are provided with pockets 2 on three sides of the opening. A simple and preferred construction of these pockets is clearly shown in Figs. 2 and 4, the pockets in this instance being formed by securing a backing 3 to the rear surface of the frame and leaving

the inner edges free for the purpose of receiving underneath them the wings 4 which are located at the marginal edges of the side wall flaps 5. The inner edges of the backing preferably terminate short of the inner edges of the frame thereby rendering the backing invisible from the front of the frame. The sign matter is drawn or printed upon a plaque 6, or on material fastened thereto, which is of the same configuration but slightly smaller in dimensions than the central opening of the frame. The side wall flaps 5 are flexibly connected to the plaque and are mitered at the ends as shown in Fig. 3 so that they may be movable independently of each other and may contact each other end to end when the device is set up. The wing 4^a which is the marginal wing upon one of the flaps is glued or otherwise permanently fastened to the back of the frame along one side of the central opening, thus holding the plaque and its flaps permanently connected to the frame.

My device is particularly useful for manufacturers who furnish their agents, jobbers or retailers with signs for advertising goods. In such cases the manufacturer ships the sign flat as shown in Figs. 3 and 5. When in this condition, the device takes up a minimum amount of space and is in convenient form for shipment. When the merchant who is going to display the sign receives it, he slips the wings 4 into the marginal recesses or pockets in the frame—a thing easily accomplished and causing the plaque to be thrown to a plane behind the plane of the frame and the flaps to meet each other end to end to thereby form a complete closure at the sides. When thus set up, the sign has an attractive appearance, giving the effect of weight and substance and being pleasing to the eye. As the frame and plaque are permanently fastened together, there is no danger of the parts becoming detached during shipment and the manufacturer has the assurance that the number of frames will always match the number of plaques, for the two parts are united during the manufacture of the device itself.

It will be noted that my device is compact for shipment and attractive when set up, and simple in construction.

Having thus described my invention, what

I claim as new and desire to secure by Letters Patent, is:

1. A device of the character described comprising a frame having a rectangular central opening, a plaque for exposure through said opening, and marginal flaps on said plaque, said frame having recesses adjacent to certain of the sides of said opening for receiving the outer edges of the flaps, of one of said flaps to the edge of the opposite flap when the flaps are in the plane of the plaque being greater than the corresponding distance between the recesses which receive the outer edges of said flaps, and the dimension of the plaque from the point where one of said flaps is joined to it to the point where the opposite one of said flaps is joined to it being less than the corresponding distance between the recesses which receive the edges of said flaps, whereby when the edges of said flaps are in place in said recesses, the flaps are thrown at an angle to the plane of the frame.
2. A collapsible sign, comprising a frame having a rectangular central opening with recesses along three sides of the internal margin thereof, a rectangular plaque bearing the sign matter, three marginal flaps on said plaque adapted to enter into said recesses, the overall dimension from the edge
3. A device of the character described comprising a frame having a rectangular central opening, a plaque slightly smaller than the opening in the frame, side walls adapted to hold the plaque parallel to and behind the plane of the frame, said walls being flexibly connected to the edges of the plaque and beveled at the ends whereby they may touch end to end when the sign is set up, said frame having pockets at the internal marginal edges for removably holding the margins of the side walls.

In witness whereof, I have hereunto subscribed my name in the presence of two witnesses.

SIEGFRIED ADLER.
